A CORPORATION OF NEW YORK.

SHEET-REGISTERING MECHANISM.

1,404,376.

Specification of Letters Patent. Patented Jan. 24, 1922.

Application filed August 19, 1920. Serial No. 404,599.

To all whom it may concern:

Be it known that we, CARL E. CHRISTOPHEL, a citizen of Germany, and FRED J. EISERMAN, a citizen of the United States, both residing at Pearl River, in the county of Rockland and State of New York, have invented certain new and useful Improvements in Sheet-Registering Mechanism, of which the following is a specification.

10 This invention relates more specifically to sheet registering devices in which the registry edge of a sheet is moved into engagement with a registering surface and has for its primary object to provide an improved construction, combination and arrangement of parts whereby a more perfect control of the sheets is secured. Particular objects of invention will appear in the specification and be pointed out in the claims, reference being 15 had to the accompanying drawings in which our invention is exemplified in a preferred embodiment. In the drawings,—

Figure 1 is a top plan view of this preferred embodiment;

25 Figure 2 is a side elevation of the same, parts being broken away and parts shown in section;

Figure 3 is a front elevation according to the line 3—3 of Figure 1, parts being shown 30 in section;

Figure 4 is a section on the line 4—4, Figure 2, parts being broken away and parts shown in elevation; and

Figure 5 is a section on the line 5—5, 35 Figure 2, parts being broken away and parts shown in section.

In the embodiment of our invention shown on the drawings, a supporting bar 1 is arranged to extend in the direction in which 40 the sheet is to be registered. As shown, the device is employed for side registering a sheet with respect to a side gage. Slidably mounted upon the bar 1 is an adjustable strap 2 which may be clamped to the bar 1 by means of a set screw 3 operated on a gib 4 which is in engagement with the bar 1. The strap 2 is provided with a hub or boss 5 through which extends a screw 6 which may be adjusted longitudinally by means of 45 knurled nuts 7. Pinned to a reduced end of the screw 6 is the hub or boss 8 of a bracket 9 which is slidably mounted on the

bar 1. The bracket 9 carries a depending arm 10 which terminates in a base-plate 11, the upper surface of said base-plate being 55 disposed in substantially the plane of feed of the sheets which are to be registered. This base-plate is provided with a groove 12 within which is reciprocably mounted a slide 13, the upper surface of said slide being in 60 the same plane with the top surface of the base-plate 11. As shown best in Figures 1, 2 and 3, a cover 14 is arranged above the base-plate 11 and slide 13, said cover being provided with an integral bearing lug 15 65 which is also integral with a lever arm 16. Said cover 14 is provided with a slot 17 which approximately registers with the groove 12. A grub or set screw 18 is adapted to engage the reduced end portion 19 of a 70 stud within the bearing lug 15. Said end portion 19 of the stud is eccentric to a journal portion 20 of said stud, which is provided with an enlarged head 21 for confining a pressure roller 22 which is journaled 75 on the portion 20. It will be seen from Figures 2 and 5 that by turning the stud in its bearing, the pressure roller 22 may be raised or lowered with respect to the cover 14, the position of said cover being thereby varied 80 with respect to the base-plate and slide whenever the pressure roller 22 is bearing against the slide 13 or upon a sheet covering said slide. A slide register gage block 23 is arranged to determine the position of the 85 lateral edge of the sheet for each registry movement. The lever arm 16 is keyed to a rock shaft 24 to which is also keyed a cam arm 25. Said cam arm 25 carries a cam roller 26 which travels over a profile cam 90 27 having a rest portion 28 for holding the pressure roller 22 and cover 14 in its extreme position away from the slide 13 and a rest portion 29 which permits said roller and cover to lie in its extreme position nearest 95 to said slide. The rest or dwell portion 29 of the oscillatory cam is provided with an extended cam surface 29' which is adapted to momentarily lift the pressure roller 22 at the inner extreme of the slide's movement so 100 that the effective action of said slide upon a sheet does not begin until the slide has begun its outward movement. The profile cam 27 has a hub portion 30 which is journalled on

a stub shaft 31 which is secured by a set screw 31' within a bracket arm 51 of the 5 slidable bracket 9. A miter gear 32 meshes with a second miter gear 33, the latter gear being splined to an oscillatory shaft 34. As shown in Figure 2, the profile cam 27 is provided with an arcuate slot 35 and with adjustable abutments 36 and 37 at opposite ends of said slot. Referring now to Figure 10 4, a lever arm 38 which is rigid with the miter gear 32, has its bearing hub 39 freely journaled upon the shaft 31 and is provided with a laterally projecting boss 40 which carries a pin 41, said pin being disposed 15 within the slot 35 of the profile cam 27. The laterally deflected end portion 42 of the lever arm 38 carries a pin 43 upon which is journaled an anti-friction roller 44. This roller 44 is disposed between spaced pins 45 (see 20 Figure 5) which project upwardly from the slide 13. It will be seen that by means of this construction, that a lost motion connection is provided between the slide oscillating lever and the profile cam 27.

25 As shown in Figure 3, the bracket 9 is provided with a curved arm 46 within which is reciprocably mounted the upper end of a spring rod 47. Said spring rod carries near its lower end a flange or collar 48 between 30 which and the arm 46 is disposed a compression spring 49. The lower end of the spring rod 47 is pivotally mounted on a pin 50 which projects laterally from the lever arm 16. By this construction, yieldable means 35 are provided which tend to hold the cover in its lower extreme position and at the same time press the cam roller 26 to the profile cam 27.

From the foregoing description, it will be 40 seen that the reciprocatory slide and the pressure roller 22 are operated in positively-timed relations to each other. A lost motion connection of predetermined amount which may be varied at will to meet requirements, 45 makes it possible to secure any desired relation between the periodical rise and fall of the pressure roller and reciprocatory movement of the slide.

We claim:—

50 1. In sheet registering mechanism, a reciprocable slide, a cam lever movable about an axis, said cam lever being provided with a pressure roller adapted to have rolling contact with said slide, and an oscillatable cam for moving said cam lever, said cam being provided with a dwell portion for holding said pressure roller away from said slide.

60 2. In sheet registering mechanism, a reciprocable slide, a cam lever movable about an axis, said cam lever being provided with a pressure roller adapted to have rolling contact with said slide, and an oscillatable cam for moving said cam lever, said cam being provided with a dwell portion for

holding said pressure roller away from said slide and another dwell portion for limiting its approach to said slide.

3. In sheet registering mechanism, a reciprocable slide, a cam lever movable about 70 an axis, a pressure roller journaled in said cam lever, an oscillatable cam operating upon said cam lever for moving said roller into and out of rolling contact with said slide, and a lever having a lost motion connection with said cam and an operating connection with said slide.

4. In a sheet registering mechanism, the combination with a fixed bar, of a bracket adjustable along said bar, a slide reciprocably mounted in said bracket, a pressure roller cooperating with said slide, a cam operated lever oscillatably mounted in said bracket, and within which said pressure roller is journaled, a shaft mounted in said 80 bracket, a cam oscillatable about the axis of said shaft and movably engaging said lever, a second lever for reciprocating said slide, said slide being provided with spaced pins between which said second lever operates, 90 and an oscillatory shaft geared to said second lever, said second lever having operating connection with said cam.

5. In sheet registering mechanism, a base 95 plate, a slide reciprocably mounted in said base plate, a cover movable towards and away from said base plate, a pressure wheel journaled in said cover for peripheral contact with said slide, and means for moving said cover towards and away from said base 100 plate and for reciprocating said slide, said moving means comprising a cam lever, an oscillatory cam for operating said cam lever, an oscillatory lever for reciprocating said slide and means for providing a lost 105 motion connection between said cam and the last-mentioned lever.

6. In sheet registering mechanism, a bracket provided with a base plate, a slide reciprocable in said base plate, a cam lever 110 journaled in said bracket, a cover mounted on said cam lever, yieldable means tending to press said cover down onto said base plate, a cam for operating said cam lever, said cam being provided with a rest portion 115 for limiting the approach of said cover to said base plate, a pressure roller journaled in said cover and adapted to have peripheral contact with said slide, and means for oscillating said cam.

7. In sheet registering mechanism, a bracket provided with a base plate, a slide reciprocable in said base plate, a cam lever journaled in said bracket, a cover mounted on said cam lever, yieldable means tending to press said cover down onto said base plate, a cam for operating said cam lever, said cam being provided with a rest portion for limiting the approach of said cover to said base 125 plate, a pressure roller journaled in said 130

cover and adapted to have peripheral contact with said slide, said cam being provided with an arcuate slot, and a lever for reciprocating said slide, said slide reciprocating lever being provided with a pin movable in said slot for oscillating said cam.

8. In sheet registering mechanism, a bracket provided with a base plate, a slide reciprocable in said base plate, a cam lever 10 journalled in said bracket, a cover mounted on said cam lever, a pressure roller journalled in said cover and adapted to have peripheral contact with said slide, yieldable means tending to press said cover down onto 15 said base plate, a cover operating cam for limiting the approach of said cover to said base plate, said cam being provided with an arcuate slot, adjustable abutments within said slot, and a lever for reciprocating said 20 slide, said slide reciprocating lever being

provided with a pin movable in said slot and between said adjustable abutments for moving said cam.

9. In a sheet registering mechanism, a reciprocable slide, a cam lever movable 25 about an axis, said cam lever being provided with a pressure roller adapted to have rolling contact with said slide, and an oscillatable cam for moving said cam lever, said cam being provided with a dwell portion for 30 holding said pressure roller away from said slide and another dwell portion for permitting its approach to said slide the last mentioned dwell portion being provided with an extended cam surface for momentarily removing the pressure roller from the 35 slide at the end of its inward movement.

CARL E. CHRISTOPHEL.
FRED J. EISERMAN.
